FIG. 6

Charles E. Lewis, INVENTOR.
BY A. Patterson, ATTORNEY.

UNITED STATES PATENT OFFICE.

CHARLES E. LEWIS, OF SAN ANTONIO, TEXAS.

COMBINED STOOL AND TABLE.

1,369,251.

Specification of Letters Patent. Patented Feb. 22, 1921.

Application filed January 10, 1920. Serial No. 350,503.

To all whom it may concern:

Be it known that I, CHARLES E. LEWIS, a citizen of the United States, residing at San Antonio, in the county of Bexar and

5 State of Texas, have invented certain new and useful Improvements in Combined Stools and Tables, of which the following is a specification, reference being had therein to the accompanying drawing.

10 This invention relates to improvements in combined stool and table, and is particularly intended for the use of automobiles and picnic parties.

The primary object of my invention is to 15 provide a combined stool and table, which is capable of being folded into a flat package, whereby it will occupy small space in transportation and is convenient to be handled; capable of being opened to form a 20 stool upon which a person may sit and a table upon which utensils and food are to be placed.

A further object of my invention is to so construct the combined stool and table that 25 a knife, fork and spoon compartments are provided when it is closed, and means provided for detachably supporting a suitable dish.

In the accompanying drawings: 30 Figure 1 is a top plan view of my combined stool and table, shown in its closed position.

Fig. 2 is an edge view of Fig. 1.

Fig. 3 is an inverted plan, showing the 35 stool and table in folded position.

Fig. 4 is a longitudinal central sectional view, the parts shown in closed positions.

Fig. 5 is a top plan view showing the stool and table in open positions ready to be 40 occupied and eaten from.

Fig. 6 is a central vertical sectional view of Fig. 5.

In carrying out my present improvement, I provide a rectangular shaped member, or 45 top A, which has depending ends and sides B', thus forming an elongated recess F', at the under side of the top or member A.

A suitable seat surface B, such as leather, is secured to the seat end of the device, and 50 secured to the under side of the top A beneath the seat B is a metal plate I. This metal plate I carries the ordinary form of folding stool legs G, which construction is so well understood that further description 55 is unnecessary. The outer end of the plate I is provided with an eye G', which encircles

the upper cross-rod H' of the legs G, and the inner end of the plate I is provided with a downwardly extending hook I' with which the other upper cross-rod J' of the legs G 60 is adapted to interlock, as shown in Fig. 6, whereby the legs are held in the position shown in that figure for supporting the combined stool and table.

The other end of the top A, opposite the 65 seat portion B, is provided with an outwardly extending recess D', into which a folding leaf A' is adapted to be folded, as shown in Figs. 1, 2 and 3. This leaf A' is hinged to the top A, by suitable hinges E', 70 and the leaf is supported in its extended position by a suitable support C.

Means is provided at the under side of the top A, beneath the seat portion D, for detachably supporting a suitable dish J, made 75 of aluminum or other material. The outer edge of this dish J, engages a transverse strip K, secured to the plate I, in any suitable manner, at a point inside of the eye G', and the inner edge of the dish J is detachably held by a pivoted latch H.

A knife, fork and spoon compartment E is provided at the under side of the top A, near the end opposite the seat portion B, by a transversely extending partition or 85 web C', and a suitable pivoted button F serves to hold these articles therein.

The folding legs G are of a length and width not exceeding the width and length of the recess F', under the top A, so that they 90 can be folded within this recess, as clearly shown in Figs. 3 and 4. When so folded, they are held in their folded position by a suitable pivoted button D.

With the above disclosed and described 95 construction, the parts can be folded into very compact flat form, as shown in Figs. 1, 2, 3 and 4, ready for transportation and will occupy little space, and can be quickly and readily opened into operative positions for 100 use.

Having thus described my invention, what I claim and desire to secure by Letters Patent is:

1. A combined stool and table, comprising- 105 an elongated body having a seat portion at one end and a table portion at its opposite end, the elongated body provided with downwardly extending sides which form an open sided hollow bottom, means 110 carried within the hollow bottom to carry and retain table articles, a plate secured

- within the hollow bottom, folding legs having one of their upper ends pivoted to the outer end of the plate, and the inner end of the plate having a hook to engage the other 5 upper ends of the legs, whereby the legs may be supported in their extended position or folded inward against the bottom of the body and within the hollow bottom thereof.
- 10 2. A combined stool and table, comprising an elongated body having a seat portion at one end and a table portion at its op-

posite end, a plate secured to the under side of the body beneath the seat portion, folding legs having one of their upper ends pivoted to the outer end of the plate, and the inner end of the plate having a hook to engage the other upper ends of the legs, whereby the legs may be supported in their extended position or folded inward against the 15 bottom of the body.

In testimony whereof I hereunto affix my signature.

CHARLES E. LEWIS.
